R. G. CLYNE ET AL

CARTRIDGE MAGAZINE LOADER

Filed April 1, 1927

Fig. 2.

UNITED STATES PATENT OFFICE.

ROBERT G. CLYNE AND GEORGE B. WILLIAMS, OF ALTON, ILLINOIS, ASSIGNEES TO
WESTERN CARTRIDGE COMPANY, OF EAST ALTON, ILLINOIS, A CORPORATION OF
DELAWARE.

CARTRIDGE-MAGAZINE LOADER.

Application filed April 1, 1927. Serial No. 180,136.

This invention pertains to a device for charging magazine tubes with rifle cartridges or the like, from which the magazine of a rifle may be loaded.

It is the practice in shooting galleries to use repeating magazine rifles, in which a number of cartridges is loaded into the magazine preparatory to firing. For convenience in loading the rifles, the cartridges 10 are first loaded into a series of magazine tubes, each tube containing the proper number of cartridges for loading a rifle. A supply of these charged tubes may be kept ready so that rifles may be rapidly loaded when 15 active firing is going on, so as to save the time of loading the magazines by hand.

The charging of the separate magazine tubes has in the past been carried on by hand, and, on account of the slow and tedious work involved, has been a considerable 20 item of expense in the operation of a shooting gallery.

One of the objects of this invention is to provide a device by means of which the magazine tubes may be charged rapidly and conveniently, without the necessity of fingering each cartridge.

Another object is to provide such a device 25 into which the cartridges may be loaded promiscuously and which will orient the same and charge them in oriented position into the magazine tube.

Another object is to provide such a device which is simple and cheap in construction and which will be easy to handle and durable in service.

Further objects will appear from the following description, taken in connection with the accompanying drawing, in which—

Figure 1 is a plan view of a charging device embodying this invention;

Figure 2 is a vertical section taken on line 2—2 of Figure 1; and

Figure 3 is a detail section on line 3—3 of Figure 1, showing the releasing mechanism.

Referring to the drawing, 1 designates a base or support, which may have a suitable foot adapted for attachment to a table or other convenient support. Mounted on the 50 support 1 is a bearing or socket 2, in which is mounted a vertical shaft or spindle 3. Mounted on the base 1, and fixed against rotation thereon, in any suitable manner, is a

guide 4. This guide is shown as generally conical in shape but may, of course, have 55 other suitable and convenient form, but is provided with an outer peripheral edge 5, forming a raceway, as will presently be more fully described. Mounted for rotation on the spindle 3 is a hub 6 carrying a spider 7, 60 which in turn carries a hopper 8. The hopper 8 is generally bowl shaped, being turned inwardly at the bottom and provided with an inner annular edge 9 opposite the edge 5 and forming a raceway, matching the raceway 65 5, so as to provide therebetween an annular aperture of constant width. The width of this aperture is adjusted to such a value that the body of a cartridge will pass freely therethrough while the enlarged head will 70 not. Consequently, a cartridge falling into this aperture will take a position with its body extending downwardly through the aperture and its head resting on the raceways 5 and 9. The latter may be suitably formed 75 to receive the head of the cartridge. In this way the cartridges become suspended in the aperture, point down.

It will be seen that, if a quantity of cartridges be charged promiscuously into the 80 hopper 8, some of them will fall through the aperture and assume a vertical position suspended therein with their points down. If, now, the hopper 8 is rotated, other cartridges will be swept across the aperture by the relative movement of the hopper and the guide 4, so that those cartridges which are positioned at the bottom of the bowl will eventually be turned to such a position that their points will drop through the aperture and 85 they will become suspended in like manner. As the hopper moves around, the suspended cartridges will be rolled along the raceway 5.

At a certain point in the raceway 5 an enlarged notch or recess 10 is formed therein. 90 This recess is large enough to permit the head of a cartridge to pass therethrough. Accordingly, as the bowl is rotated and the cartridges are rolled along the raceway 5, as each cartridge arrives at the recess 10, it 100 will be permitted to drop therethrough and thus be released from the hopper. A guard or bridge 11 is fixed to the guide 4 in such a way as to extend over the aperture 10, allowing sufficient clearance for the head of a 105 cartridge to pass therebeneath. This guard

or bridge 11 prevents any cartridge from going through the aperture 10 head first, supports the pressure of the cartridges piled thereabove in the hopper and protects the 5 cartridge to be released from such pressure as it passes to position at the recess 10. Accordingly, just before each cartridge is released, it is freed from any interfering pressure of the accumulated cartridges in the 10 hopper. This insures a free fall of the cartridge through the recess 10. A stop 12 may also be fixed to the guard 11 below the aperture and in such a position as to prevent a cartridge from overshooting and passing 15 the notch 10.

Mounted on the support 1 is a holder 13 adapted to receive a receptacle in the form of a magazine tube 14. The holder 13 is provided with a vertical bore into which the 20 receptacle 14 may be inserted and the upper part of which may be provided with a flared funnel tube 15, so as to provide a funnel into which the cartridges may drop. The holder 13 may be provided with a retaining 25 latch or spring 16 provided with a keeper 17 adapted to enter a suitable notch 18 in the receptacle 14 in order to retain the same in the holder. A bowl 19 may be formed on the upper part of the holder 13 to receive any 30 overflow of cartridges from the funnel 15.

In the operation of this device, a receptacle 14 is inserted in the holder 13. A supply of cartridges is placed in the hopper and the latter rotated slowly. The relative movement 35 between the hopper and the guide 4 causes the cartridges to become suspended in the aperture, as previously explained. The suspended cartridges are moved along the aperture to the releasing point at the 40 recess 10, where each cartridge is released, dropping through said recess and into the receptacle 14. When the required number of cartridges has been delivered to the receptacle, the rotation of the hopper is stopped 45 and the receptacle withdrawn. As the receptacle is withdrawn, the keeper 17 snaps into engagement with the last cartridge above the receptacle 14 and retains the latter until a new receptacle is inserted. When such insertion 50 takes place, the keeper 17 is moved out of engagement with the cartridges in the holder 13 and the latter are permitted to drop into the receptacle. A sight opening 55 may be provided in order that the operator may tell when the receptacle is full.

It will be seen that this invention provides a simple and effective device by means of which magazine tubes may be quickly charged so as to be ready for loading the 60 rifles. The relative movement of the hopper and the guide causes the cartridges to be oriented and suspended in the raceway and then moved around to the delivery point, where they are released and dropped into 65 the receptacle. As the cartridge approaches

the point of release, the pressure of the mass of cartridges above it in the hopper is removed therefrom so as to permit it to drop freely.

It is obvious that various changes may be 70 made in the details of construction without departing from the spirit of this invention; it is to be understood, therefore, that this invention is not limited to the specific details shown and described. 75

Having thus described the invention, what is claimed is:

1. A device for charging cartridge magazine tubes, comprising, a hopper, a guide therein, an aperture between said hopper and said guide, and means for moving said hopper and said guide relatively adapted to cause cartridges in said hopper to become oriented in said aperture. 80

2. A device for charging cartridge magazine tubes, comprising, a hopper, a guide therein, an aperture between said hopper and said guide, means for moving said hopper and said guide relatively adapted to cause cartridges in said hopper to become oriented in said aperture, and means for releasing the oriented cartridges. 85

3. A device for charging cartridge magazine tubes, comprising, a hopper, a guide therein, an aperture between said hopper and said guide, means for moving said hopper and said guide relatively adapted to cause cartridges in said hopper to become oriented in said aperture, means for releasing the oriented cartridges, a receptacle holder adjacent said releasing means, and means for feeding a released cartridge to said receptacle. 95

4. A device for charging cartridge magazine tubes, comprising, a hopper, a guide therein, an annular aperture between said hopper and said guide, means for rotating said hopper and said guide relatively adapted to cause a cartridge in said hopper to become oriented in said aperture, means for suspending the oriented cartridge in said aperture, and means for releasing the suspended cartridge. 105

5. A device for charging cartridge magazine tubes, comprising, a hopper, a guide therein, an annular aperture between said hopper and said guide, means for rotating said hopper and said guide relatively adapted to cause a cartridge in said hopper to become oriented in said aperture, means engaging an enlarged portion thereof for suspending the oriented cartridge in said aperture, and means for releasing the suspended cartridge. 115

6. A device for charging cartridge magazine tubes, comprising, a hopper, a guide therein, an aperture between said hopper and said guide, means for moving said hopper and said guide relatively adapted to cause cartridges in said hopper to become oriented in said aperture, means 120

- for releasing the oriented cartridge, a receptacle holder adjacent said releasing means, means for feeding a released cartridge to said receptacle, and means for releasably retaining a receptacle in said holder.
7. A device for charging cartridge magazine tubes, comprising, a hopper, a guide therein, an aperture between said hopper and said guide, means for moving said hopper and said guide relatively adapted to cause cartridges in said hopper to become oriented in said aperture, means for releasing the oriented cartridge, a receptacle holder adjacent said releasing means, means for feeding a released cartridge to said receptacle, and means for releasably retaining a receptacle in said holder adapted to retain the cartridges when the receptacle is removed.
- 20 8. A device for charging cartridge magazine tubes, comprising, a hopper having an annular raceway, a guide therewithin having a raceway matching said first raceway and forming therewith an annular aperture adapted to receive a cartridge to be suspended therein, means for rotating said raceways relatively adapted to orient a cartridge in said hopper and cause the same to become suspended therein, and means for releasing the suspended cartridge.
9. A device for charging cartridge magazine tubes, comprising, a hopper, a guide therein, an aperture between said hopper and said guide, means for moving said hopper and said guide relatively adapted to cause cartridges in said hopper to become oriented in said aperture, means for releasing the oriented cartridges, and a guard for said releasing means.
- 40 10. A device for charging cartridge magazine tubes, comprising, a hopper, a guide therein, an aperture between said hopper and said guide, means for moving said hopper and said guide relatively adapted to cause cartridges in said hopper to become oriented in said aperture, and supporting means adapted to protect the cartridge to be released from pressure of other cartridges in said hopper.
- 50 11. A device for charging cartridge magazine tubes, comprising, a hopper, a guide
- therein, an aperture between said hopper and said guide, means for moving said hopper and said guide relatively adapted to cause cartridges in said hopper to become oriented in said aperture, a releasing aperture connected with said first aperture, and a guard over said releasing aperture.
12. A device for charging cartridge magazine tubes, comprising, a hopper, a guide therein, an aperture between said hopper and said guide, means for moving said hopper and said guide relatively adapted to cause cartridges in said hopper to become oriented in said aperture, means for releasing the oriented cartridge, and a stop adapted to prevent a cartridge passing the releasing point.
13. A device for charging cartridge magazine tubes, comprising, a rotatable hopper, a circular guide therein, said hopper having an opening adapted to form with said guide a slot through which the body of a cartridge may pass but which will retain the head thereof, and means on said guide adapted to effect the release of a cartridge from said slot.
14. A device for charging cartridge magazine tubes, comprising, a rotatable hopper, a circular guide therein, said hopper having an opening adapted to form with said guide a slot through which the body of a cartridge may pass but which will retain the head thereof, a receiver below said slot, and means on said guide adapted to effect the release of a cartridge from said slot, so as to drop into said receiver.
15. A device for charging cartridge magazine tubes, comprising, a rotatable hopper, a circular guide therein, said hopper having an opening adapted to form with said guide a slot through which the body of a cartridge may pass but which will retain the head thereof, a receiver below said slot, means on said guide adapted to effect the release of a cartridge from said slot so as to drop into said receiver, and means for mounting a magazine tube in said receiver.

In testimony whereof we affix our signatures this 16th day of March, 1927.
